UNITED STATES PATENT OFFICE.

JOSEPH L. NYLANDER, OF SEATTLE, WASHINGTON.

ELECTRIC HEATER.

1,062,111.

Specification of Letters Patent.

Patented May 20, 1913.

Application filed November 27, 1912. Serial No. 733,914.

To all whom it may concern:

Be it known that I, JOSEPH L. NYLANDER, a citizen of the United States, residing at Seattle, in the county of King and State of Washington, have invented certain new and useful Improvements in Electric Heaters; and I do hereby declare the following to be a full, clear, and exact description of the invention, such as will enable others skilled in the art to which it appertains to make and use the same.

This invention relates to electric heaters for flowing water; and it consists in the novel construction and combination of the parts hereinafter fully described and claimed whereby the heater is specially adapted for hospital use.

In the drawings, Figure 1 is a side view partially in section, showing a heater constructed according to this invention. Fig. 2 is an end view of the heater.

The water is heated in a flexible pipe 2 formed of india rubber or other suitable material. The pipe 2 is provided with a catheter or spray nozzle 3 as ordinarily used for administering injections.

In order that the water may be delivered hot, the heater is applied to the water pipe 2 as close as possible to its nozzle, and it is slidable upon the said pipe. A metallic heating tube 4 is arranged to slide in contact with the water pipe 2, and a suitable electrical resistance body or coil 5 is arranged around the heating tube and is provided with circuit wires 7 and 8, which are connected to an electric lighting fixture or other convenient source of electric current.

Caps 10 of insulating material are secured upon the ends of the heating tube 4, and 12

is a cylinder of wire gauze secured to the caps and forming a chamber 14 around the resistance coil. The cylinder of wire gauze is stiffened by means of one or more bands or rings 15, or other suitable stiffeners.

The water is supplied to the water pipe 45 from any suitable reservoir or boiler in which it may be heated to any desired extent, and additional heat is imparted to the water by the electric heater which is arranged in the bed and as close as convenient 50 to the body of the patient. The cylinder of wire gauze protects the bed clothing, and the heated air escaping from it indicates to the hand when the heater is working properly.

The flexible water pipe can be renewed as often as necessary.

What I claim is:

In a device for administering injections, the combination, with a flexible pipe provided with a catheter at its outlet end, of a handle of wire gauze encircling the said pipe, caps secured to the ends of the said handle, a heating tube secured to the said caps and slidable by means of the said handle upon the flexible pipe, a resistance coil encircling the said heating tube, an air space being formed between the resistance coil and the handle, and a stiffening ring secured to the middle part of the handle to prevent the wire gauze from being collapsed by the pressure of the hand.

In testimony whereof I have affixed my signature in the presence of two witnesses.

JOSEPH L. NYLANDER.
